UNITED STATES PATENT OFFICE.

JULIUS M. REIS, OF NEW YORK, N. Y.

DESIGN FOR AN EMBROIDERY FOUNDATION.

44,147.

Specification for Design.

Patented June 3, 1913.

Application filed April 4, 1913. Serial No. 758,948. Term of patent 8½ years.

To all whom it may concern:

Be it known that I, JULIUS M. REIS, a citizen of the United States, and a resident of New York city, county of New York, and State of New York, have invented a new, original, and ornamental Design for Embroidery Foundations, of which the following is a specification, reference being made to the accompanying drawing, forming part thereof.

The figure is a plan view of an embroidery foundation, showing my new design (T).

I claim—

The ornamental design for an embroidery foundation as shown.

In testimony whereof, I have signed my name to this specification, in the presence of two subscribing witnesses.

JULIUS M. REIS.

Witnesses:

WILLIAM A. HERRMANN,
A. E. HASKINS.

Copies of this patent may be obtained for five cents each, by addressing the "Commissioner of Patents, Washington, D. C."

UNITED STATES PATENT OFFICE.

RALPH WORMS, OF CHICAGO, ILLINOIS, ASSIGNOR TO WORMS & LOEB, OF CHICAGO, ILLINOIS, A CORPORATION.

DESIGN FOR A BRACELET.

44,047.

Specification for Design.

Patented May 13, 1913.

Application filed March 10, 1913. Serial No. 753,436. Term of patent 3½ years.

To all whom it may concern:

Be it known that I, RALPH WORMS, a citizen of the United States, residing at Chicago, in the county of Cook and State of Illinois, have invented a new and original Design for Bracelets, of which the following is a specification, reference being had to the accompanying drawing, forming part thereof.

In the drawing, Figure 1 is a perspective view of a bracelet showing my new design.

Fig. 2 is a plan view of the same with the outer side portion of the bracelet shown in central, horizontal section.

I claim:

The ornamental design for a bracelet, as shown.

RALPH WORMS.

Witnesses:

LOUIS M. F. WHITEHEAD,
KATHARINE GERLACH.

Copies of this patent may be obtained for five cents each, by addressing the "Commissioner of Patents, Washington, D. C."
